UNITED STATES PATENT OFFICE

JOHN G. L. SKAR, OF JAMESTOWN, AND HAROLD J. SYREN, OF BUFFALO, NEW YORK,
ASSIGNORS TO ART METAL CONSTRUCTION COMPANY, OF JAMESTOWN, NEW YORK

STORAGE SYSTEM

Application filed March 12, 1929. Serial No. 346,346.

This invention relates to systems for storing various articles such as books or the like, and has for an object to provide an improved construction by which the articles may be stored in a compact manner, with each stored article easily and quickly accessible.

A further object is to provide an improved system, of the type in which the articles are stored in separate frames that may be arranged closely side by side in a row, and each frame individually pulled laterally out of the row, when desired, to permit access to be had to the sides or faces of the frame upon which the articles are stored.

15 A further object of the invention is to provide an improved system utilizing rolling supports that may be guided in a prescribed path and moved with a minimum of effort; with which the supporting and guiding means will not interfere materially with the capacity of the support; and with which there will be no material obstructions over which one may stumble when moving around the supports.

20 A further object of the invention is to provide an improved means for supporting and guiding a frame in a prescribed path across the floor of a room; which will not project materially above the floor of the room; and with which collection of dirt or similar foreign matter on the floor will not materially interfere with the operation of the frame.

25 A further object of the invention is to provide an improved rail and roller for supporting and guiding an object across the floor of a room; with which the rail may be substantially flush with the upper face of the floor; with which the collection of dirt upon the rail will not materially block the operation of said roller therealong; with which dirt 30 collecting upon the rail will be removed by the passage of the roller thereover; and which will not materially interfere with the regular sweeping or cleaning of the floor.

35 A further object of the invention is to provide an improved rolling support for objects, which may be formed of structural steel, and which will be relatively simple, convenient and inexpensive.

40 Various other objects and advantages will 50 be apparent from the following description

of an embodiment of the invention, and the novel features will be particularly pointed out hereinafter in connection with the appended claims.

In the accompanying drawings:—

55 Fig. 1 is a sectional elevation through a portion of a room, illustrating the mounting of rolling book stacks in accordance with this invention;

60 Fig. 2 is a sectional elevation through the room, approximately crosswise of the parts shown in Fig. 1, the section being taken approximately along the line 2—2 of Fig. 1;

65 Fig. 3 is an elevation of the rail guides for the lower part of each frame, on a somewhat larger scale than shown in Fig. 1;

Fig. 4 is an elevation, partly in section, illustrating the means for guiding the upper portion of a frame;

70 Fig. 5 is a sectional elevation of part of a frame or carriage and its support, the section being taken approximately along the line 5—5 of Fig. 1;

75 Fig. 6 is a sectional elevation of the means for supporting the upper end of a frame or carriage, the section being taken approximately along the line 6—6 of Fig. 1; and

80 Fig. 7 is a sectional plan through the lower part of a carriage or support to illustrate the mounting of a roller, the section being taken approximately along the line 7—7 of Fig. 5.

85 In the illustrated embodiment of the invention, the book stacks or frames 1 are arranged side by side in rows, as shown in Fig. 2, and also if desired, two abreast in such rows as shown in Fig. 1.

90 Each stack or frame 1 is in the nature of a carriage and includes a rectangular frame formed of tubular end posts 2, a top connecting bar 3, and angle bars 4 extending along and connected to opposite sides of the lower ends of the posts 2.

95 Suitable shelves 5 are secured to said frame in a manner to project from opposite faces thereof, as shown in Fig. 2. A pair of rollers or wheels 6 are disposed at the bottom of each frame, preferably between the opposite faces thereof, and rotatably attached to the frame so as to serve as rolling supports and guides 100

for the frame. The two wheels 6 at the lower end of each frame are arranged in tandem to roll about horizontal axes in the same direction and along the same path.

5 A rail 7 is disposed beneath each frame or carriage and crosswise of the row, and the wheels or rollers 6 ride upon or are guided by the related rails 7. Each rail 7 is approximately flush with the upper face 8 of the floor of the room, and its upper face may 10 be provided with a V-shaped groove 9 running lengthwise of the rail. Each wheel or roller 6 may have a peripheral V-shaped flange 10 which runs in the groove 9, while the remaining periphery of the wheel or roller 6 may roll upon the upper surface of a rail 7. The flange 10 serves to guide the roller along the rail and confine it thereto.

One or more studs 11 (Figs. 2, 4 and 6) 20 are provided upon each frame, so as to extend upwardly into the interior of an inverted channel strip or rail 12 which is parallel to each lower rail 7 and which extends above each frame or carriage 1. The studs 11 25 may have their heads countersunk into L-shaped plates 11a which are fitted over the upper corners of each frame and secured thereto by screws 11b (Figs. 4 and 6). The studs also are provided with shoulders 13 30 some distance below their upper ends, and these shoulders may be formed by placing sleeves or bushings over the studs. Each stud mounts a roller 14 which rests upon the shoulder 13.

35 The rollers 14 may be removably confined upon the studs in any suitable manner, such as by cotter pins 15 passing through the studs above the rollers 14. Each roller 14 runs along the interior of the inverted channel of the strip 12 above that frame or carriage, and 40 engages the inner faces of the opposite sides or arms of the channel strip, so as to maintain the frame in an upright position and assist in guiding it in a path crosswise of the row of carriages or frames.

45 Thus the book stacks or frames 1 may be arranged closely to one another in the row, and each frame or stack moved laterally and outwardly of the row to expose its opposite faces or sides in order that one may have access to the shelves. When the rows of carriages or frames are spaced apart from one another by aisles, each individual stack or carriage may be pulled outwardly into the 50 aisle between adjacent rows. This provides a maximum storage space for books or similar articles over a minimum of floor space, and with all of the articles or books easily accessible for inspection, removal or replacement.

55 The upper channel strips 12 may be connected by angle members 16 to supports 17 depending from the ceiling of the room, as shown clearly in Fig. 1. Where the carriages or stacks are arranged two abreast in 60 a row, each channel strip 12 may have a stop

18 secured therein for engagement by the rear roller 14 of the frames or carriages guided by that strip. These stops 18 determine the positions of the frame in the row and avoid collisions between the frames of each pair abreast when either frame of that pair is returned to its position in the row.

70 Each lower rail 7 may also be formed of an inverted channel strip having the groove 9 depressed into the upper face of the bottom or cross wall of the channel strip, as shown clearly in Fig. 5, and the free edges of the depending arms of the channel may be provided with lateral flanges 19 which rest upon suitable supports 20, such as beams of the floor, and may extend beneath the upper flooring strips 21. The depth of the channel strip forming the rail 7 would then be approximately the thickness of the flooring strips 21, so that the upper face of the rail 7 will be approximately flush with or on a level with the upper face of the flooring strips.

75 If desired a suitable stop 22 may be provided along each rail 7, below the stops 18, for engagement by resilient buffers 22a on the frames of each pair, to determine their position in the row and prevent collisions between the abreast members of each pair. The frame posts 2 may be formed of channel strips 2a and 2b, which are disposed edge to edge, with the channels opening towards one another, as shown in Fig. 7, to make a tubular post.

80 The abutting edges of the channel strips 2a and 2b may be flanged laterally and outwardly as at 23 to facilitate their connection to one another, and to provide means for the attachment of the shelves 5. The lower ends of these posts may be reinforced by angle members 24 which may be welded to one of the channel strips, such as 2b. The angle members 24 are disposed between the cross angle bars or strips 4 of the frame and the sides of the tubular posts 2, and bearing pivots 25, which may be in the nature of bolts, pass through the side angle bars or strips 4, the angle members 24, the sides of the channel strips 2b and through the rollers or wheels 6. Thus each bolt 25 serves, not only to clamp the various structural elements together in forming the frame with a wheel 6 forming a spacer, but also serves as a pivot bearing for its roller or wheel 6.

85 The rollers or wheels 6 preferably do not project outwardly beyond the ends of the frame, and the bottom or cross walls of the channel strips 2b may have notches 26, Fig. 5, cut therein from the lower end to provide clearance for the wheels or rollers 6. A handle 27 may be secured to the outer end post 2 of each carriage at a suitable height to facilitate the pulling out or replacement of that carriage.

90 It will be observed that since the lower

5 rails 7 are approximately flush with the upper face of the floor, there will be nothing upon which one is likely to stumble or trip when walking across the floor, and there will be no obstructions to the movement of portable carts through the aisles between rows, when books or articles are being carried to and from stacks or storage places, as usual in libraries for example.

10 The lower rails will also not offer any material obstruction to the sweeping or cleaning of the floors, and if any material quantity of dirt or similar foreign matter should collect in any V-shaped groove 9, such dirt or foreign matter will be forced out of the groove by the wedging action of the V-shaped flange 10, as the wheels or rollers 6 roll along the rail. This prevents the packing of dirt or foreign matter in the grooves to the extent that the grooves would have no guiding effect upon the flanges 10. The rollers 6 will be largely supported upon the flat upper faces of the rails 7 and confined thereto and guided therealong by the engagement of the flanges 25 10 with the grooves 9.

By placing the lower rollers or wheels 6 approximately centrally between opposite side faces of the frame, the rollers or wheels may be made relatively large in diameter and therefore they will roll easily and freely, and but a minimum of effort will be required to move the frames or stacks 1 into or out of their positions in a row.

35 The guides at the tops of the stacks maintain the stacks or frames in upright positions, as they travel into and out of position in the row, and enable the use of a minimum number of rollers beneath each carriage.

40 By supporting the stacks or frames at both top and bottom they do not become top heavy and unstable when made of considerable height, and the stacks may therefore extend practically to the ceiling of the room.

45 It will be obvious that various changes in the details which have been herein described and illustrated in order to explain the nature of the invention, may be made by those skilled in the art within the principle and scope of the invention as expressed in the appended claims.

Claims:—

1. In a storage system for articles such as books and the like, a room having parallel trackways along the ceiling and floor, a plurality of carriages arranged side by side closely to one another in rows running crosswise of the tracks, and each mounted on a floor track, and guided by a ceiling track, whereby any carriage may be pulled laterally from its row to make both side faces easily accessible for storage or removal of articles.

2. In a storage system for articles such as books and the like, a plurality of carriages arranged side by side in a row, each carriage

having a central vertical frame with rollers at the bottom thereof, in approximately the same plane with one another, and rolling in a direction laterally of the row, means engageable with the upper edge of the frame for 70 guiding it laterally into and out of said row and keeping it upright in all positions, whereby any carriage in a row may be pulled laterally out of the row to make both of its side faces easily accessible.

3. In a storage system for articles such as books and the like, a plurality of carriages arranged side by side in a row, each carriage having rollers at the bottom thereof arranged in a row transversely of the first mentioned 80 row and approximately centrally between the two sides of the carriage, for supporting the carriage and guiding it laterally into and out of that row, and a guide rail arranged above each carriage and extending crosswise of said 85 row for maintaining the carriages in upright positions during their movements, whereby any carriage in said row may be pulled out of that row to make both of its side faces easily accessible.

4. In a storage system for articles, such as books and the like, a plurality of carriages arranged side by side in a row, a rail above and below each carriage and extending crosswise of said row, wheels provided 95 upon the lower portion of each carriage and engaging with the rail below that carriage for supporting the carriage and guiding it laterally into and out of a position in the row, and means provided upon the upper 100 part of each carriage and cooperating with the upper rail for maintaining the carriage in an upright position as it moves into and out of said row.

5. A storage system for articles such as books and the like and of the type having a plurality of carriages arranged side by side in a row, which comprises a carriage, a rail above and below each carriage and running crosswise of said row, a plurality of 105 rollers provided at the lower end of said carriage and running on the lower rail to guide the carriage laterally into and out of said row, the upper rail comprising an inverted channel and a roller mounted on the 110 carriage and running in said inverted channel and against the side walls thereof for guiding the upper end of said carriage into and out of said row and maintaining said carriage upright while in all positions.

6. In a storage system for articles, such as books and the like, a room having a floor, a plurality of carriages arranged side by side in a direction across said room, a rail on said floor beneath each carriage and running crosswise of the row, each rail having a V-shaped groove in its upper surface, and a roller attached to each carriage and running on the rail beneath that carriage, with a V-shaped peripheral portion entering said V- 130

shaped groove to guide the roller along the rail.

7. In a storage system for articles such as books and the like, a room having a floor, a plurality of carriages arranged side by side in a row in said room, a rail on said floor beneath each carriage and running crosswise of said row, the upper face of each rail being approximately flush with the upper face of the floor and having an approximately V-shaped groove in its upper face, roller means carried by each carriage and running upon said rail to support said carriage and guide it laterally into and out of said row, each roller means rolling upon its rail with a peripheral V-shaped portion thereof running in said groove to guide the carriage along the rail.

8. A storage system for articles such as books and the like, a carriage comprising a rectangular frame with shelves projecting from opposite faces thereof, a wheel rotatably attached to the lower portion of said frame between the opposite faces of the frame for supporting and guiding said frame laterally into and out of said row, and means engageable with the upper portion of the frame for keeping the frame upright and guiding it into and out of its position in said row.

9. In a storage system for articles, such as books and the like, a plurality of carriages arranged side by side in a row, each carriage having a vertical frame, a rail above and below each carriage and running crosswise of said row, said carriages having rollers at their lower ends and engaging with the lower rails, and rollers carried by the upper ends of said carriages and engaging with the upper rails to keep the carriages upright and to guide them laterally into and out of said row.

10. In a storage system for articles, such as books and the like, a plurality of carriages arranged side by side in a row, each carriage having a vertical frame, a rail above and below each carriage and running crosswise of said row, said carriages having rollers at their lower ends and engaging with the lower rails, and rollers carried by the upper ends of said carriages and engaging with the upper rails to keep the carriages upright and to guide them laterally into and out of said row, said lower rails having V-shaped grooves in their upper faces, and the lower wheels having V-shaped peripheral portions running in said grooves to guide the lower portions of said carriage in a definite path.

11. In a storage system for articles, such as books and the like, a plurality of carriages arranged side by side in a row, each carriage having a vertical frame, a rail above and below each carriage and running crosswise of said row, said carriages having rollers at their lower ends and engaging with the lower

rails, and rollers carried by the upper ends of said carriages and engaging with the upper rails to keep the carriages upright and to guide them laterally into and out of said row, said upper rails comprising inverted channel strips, and the rollers on the upper ends of the carriages running in the inverted channels and engaging with the inner face thereof.

12. In a storage system for articles such as books and the like, a storage frame, a channel strip disposed beneath said frame in an inverted position and having a V-shaped groove in the upper face thereof, the lower edges of the channel arms being flanged to provide anchorage means for securing the channel strips in position, and roller means provided on said carriage and running on said upper face and guided in a prescribed path by said V-shaped groove.

13. In a storage system for articles, such as books and the like, a carriage, a rail extending beneath the carriage and having a V-shaped groove in its upper face, roller means carried by the lower portion of the carriage and having a peripheral V-shaped portion running in said groove to guide said carriage in a prescribed path.

14. In a storage system for articles such as books and the like, a carriage frame, a rail extending beneath the carriage and having a V-shaped groove along the upper face of the same, a roller attached to said carriage running upon the upper face of said rail, with a V-shaped peripheral flange running in said groove to confine the roller to the rail.

15. In a storage system for articles, such as books and the like, a plurality of carriages arranged side by side in a row by pairs, rails extending crosswise of said row above and below each pair, rolling means attached to said carriage and engageable with the upper and lower rails for guiding each carriage laterally of the row into and out of a position in the row, and a stop carried by one of the rails for each pair of carriages in a position to be engaged by the carriages running on that rail for defining the positions of the carriages in the row and preventing the pushing of one carriage out of a position in the row when the other carriage in that pair is pushed into position.

16. In a storage system for articles such as books and the like, a room having a floor, a plurality of carriages arranged side by side in a row, a plurality of rails each extending one beneath each carriage and running crosswise of said row, each rail being substantially flush with the upper surface of said floor, and a flanged wheel attached to each carriage and running on said rail so as to guide the carriage into and out of position in said row.

17. In a storage system for articles, such as books or the like, a carriage comprising a vertical frame having article supports extending from opposite faces thereof, a supporting

and guiding roller attached to the lower part of the frame and disposed between the faces of said frame, and means engageable with the upper edge of said frame for also guiding said frame in a prescribed path, and keeping it upright in all positions.

5 18. In a storage system for articles, a frame comprising spaced vertical tubular posts, bars extending along opposite sides of the lower ends of said posts and secured thereto, a roller disposed within each post at the lower end thereof and between said bars, and bearing means for each roller passing through the adjacent post and bars.

10 19. In a storage system for articles, a carriage frame, a rail beneath said frame, roller means running on said rail and supporting and guiding said carriage along the rail, a stud projecting upwardly from said frame and having a shoulder, a roller rotatably mounted on said stud above the shoulder, and an inverted channel strip running parallel to said rail but above said carriage, with its arms depending on opposite sides of said roller, whereby said channel strip and roller will maintain said frame in an upright position during its movement along said rail.
